UNITED STATES PATENT OFFICE.

CLARK W. PARKER, OF NEW YORK, N. Y.

DESIGN FOR A FRAME FOR CIGARETTE LIGHTING AND VENDING MACHINE.

Application filed June 20, 1928. Serial No. 27,209. Term of patent 14 years.

To all whom it may concern:

Be it known that I, CLARK W. PARKER, a citizen of the United States, residing in the borough of Manhattan, city, county, and State of New York, have invented a new, original, and ornamental Design for Frame for Cigarette Lighting and Vending Machine, of which the following is a specification, reference being had to the accompanying drawing, forming part thereof.

frame for cigarette lighting and vending machines embodying my new and ornamental design;

Figure 2 is a view showing the design of Figure 1 in side elevation.

I claim:

The ornamental design for a frame for cigarette lighting and vending machine, as shown.

CLARK W. PARKER.
